UNITED STATES PATENT OFFICE.

SAMUEL MARCUS, OF BROOKLYN, NEW YORK, ASSIGNOR TO MARKON MANUFACTURING CO., INC., OF NEW YORK, N. Y., A CORPORATION OF NEW YORK.

TOOL FOR USE IN ATTACHING TONGUES AND TEETH IN DOLL HEADS.

Application filed October 4, 1927. Serial No. 223,940.

This invention relates to a tool for use in attaching a tongue and teeth set in doll heads and the like, and an object of the invention is to provide a tool having a part disposed for receiving the doll head thereover and said part being constructed to support the set in proper position to facilitate the attachment of the set within the head.

A further object is to provide a tool including a part by which pressure may be readily and accurately applied to effect attachment of the set within the head and further to so arrange said part that it may be readily moved to a position out of use whenever its employment is not desired.

A further object is to provide means whereby the position of the set upon the tool may be adjusted to best facilitate attachment into heads having different structural contours.

A further object is to provide means for insuring accurate positioning of the set upon the tool.

A further object is to provide means by which to adjustably determine the position of the head upon the tool.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a side elevational view of a tool constructed in accordance with this invention, and illustrating the same in association with a tongue and teeth set and a doll head all as in a position of use, certain parts being shown in vertical section.

Fig. 2 is an enlarged vertical sectional view through the set carrying portion of the tool and illustrating a tongue and teeth set in position thereon.

Fig. 3 is a top plan view of the portion of the tool seen in Fig. 2, a part of the set being shown in horizontal section in association therewith.

Fig. 4 is a perspective view of a tongue and teeth set detached, and

Fig. 5 is a side elevational view of a modi-

fied form of tongue and teeth set in which attaching tangs are shown as a medium of attaching the set to the doll head.

Referring to the drawings for describing in detail the structure therein illustrated the reference character L indicates a suitable base from which rises a standard G. Projecting laterally from this standard is a set-carrier supporting arm 1 at the outer end of which is mounted the set-carrier H.

The set-carrier may be attached to the arm 1 in any appropriate manner, either rigidly or otherwise as may be preferred, but in the instance illustrated it is shown to be pivotally mounted upon a horizontal pivot member 2 carried by the end of the arm. The carrier extends below the pivot 2 and has an arculate slot 3 within which engages a set screw 4 said parts providing for adjustable movement of the carrier about the pivot 2 and convenient retention of the carrier in any position of adjustment to which it may be moved within the limits of the slot 3.

The carrier projects also above the pivot 2 and its upper surface is adapted to directly support the tongue and teeth set indicated generally by the reference character 5.

The set-carrying surface or portion of the carrier will vary in different respects according to the construction or form of the set which it is designed to attach. In the instance illustrated its upper surface includes what may be referred to as a main or anvil portion 6 upon which the main or base part 7 of the set is intended to rest. A protuberance as 8 extends upwardly from this anvil surface being appropriately shaped to fit within the hollow tongue part as 9 of the set. And a depression as 10 is provided for receiving a downwardly extending part as 11 of the teeth member of the set.

It is noted that the tongue and teeth set illustrated herein and which the present set-carrier H is designed to apply conforms with the set shown and described in the pending application of Samuel Marcus, Serial No. 143,031, filed October 21st, 1926, in that it includes the main base portion 7 having the protruding hollow tongue portion 9, a slit as 12 being formed through the base 7 above the tongue portion to accommodate the portion 11 of the teeth member 13. The base 7 has a reduced extension 14 by which it may be connected with the inner surface of the doll head, said extension being flexible so that

if desired the remainder of the structure may have flexible connection therethrough with the doll head, this feature being for the purpose of enabling the tongue part 9 to be 5 pressed back by a child in play without injury to the set, all as more fully described in said co-pending application.

The main base portion 7 may if desired be also cemented firmly to the head.

- 10 The anvil surface 6 preferably extends to underlie substantially all of the base portion 7 of the set, including the extension 14 thereof, and the depression 10 is of such a size that its opposite side walls as 15—15 may be engaged by the opposite edges of the extension 11 to thereby assist in properly positioning the set upon the carrier, said walls and extension constituting co-operative guide parts so removed from the protuberance 8 as to materially assist the protuberance in guiding and retaining the set in a precise relation to the carrier.

It will be understood that the set may be attached to the doll head either by the use of 25 a cementitious material as indicated at 16 in Fig. 2, or by the use of tangs or other fastening devices 17 as indicated in the illustration Fig. 5.

Where the cementitious material is employed it may be applied onto the upper surface of the extension 14, or elsewhere preferably after the set has been placed onto the anvil surface of the carrier. The subsequent 30 positioning of the head over the set and into contact with the cementitious material will result in attachment of the set onto the head. Suitable pressure for moving the head against the cementitious material and the set for this purpose may be applied either by 40 hand pressure of the operator directly against the head, or by the use of a suitable pressure lever as 18.

Where the tangs as 17, or the like, are employed the cementitious material may or may 45 not be used, and the necessary pressure in this instance would preferably be applied by means of the lever 18 although if preferred the operator may use direct hand pressure against the head.

50 The pressure lever 18 may be mounted in any appropriate manner but as indicated it is pivotally connected as at 19 to an extension part as 20 from the standard G and it has carried thereby a cushion element as 21 disposed for 55 directly engaging against the mouth portion of the head for preventing injury to the surface of the head. A hand grip part as 22 extends to a suitable position to be conveniently grasped by the operator.

60 Whenever this lever is not desired the operator may dispose of its presence by simply throwing it back about its pivot into approximately the position as indicated by the dotted lines in Fig. 1, it being supported in that position by a suitable stop or the like as 23 from

whence it may be as conveniently swung again into operative position whenever desired.

In order to assist the operator in correctly and uniformly positioning a series of heads successively upon the tool a suitable rest as 24 70 is provided as a part of the tool. This rest is adjustable to accommodate itself to varying requirements as to the contours and characteristics of different types of doll heads and in the instance illustrated is shown to consist of 75 a simple slideable wedge carried upon the upper surface of the carrier arm 1, being longitudinally movable along said surface to dispose parts of selected thickness in position for engagement by the doll head. An extension part 25 is provided with a slot 26 within which engages a set screw 27 for retaining the rest and for holding it in any position to which it may be adjusted longitudinally of the arm 1. By adjustably moving the carrier 80 H upon its pivot 2 and by properly adjusting the rest 24 the doll head and the tongue and teeth set therefor may be held in just the right 85 co-operative relationship preparatory to attachment. It is noted that by utilizing a rest 90 which is of wedge shape and in the relation as indicated said rest provides an upper surface as 28 which inclines in a direction such that it serves naturally to urge the doll head in a direction so that the lower lip part as 29 of the 95 mouth opening of the head is urged against the tongue part of the set, thereby incidentally urging the upper lip part 30 of the mouth opening of the head away from the tongue portion and exhibiting the teeth member of 100 the set, as is of course the proper and desired relationship of these parts.

It is further noted that the teeth member 13 of the set stands in an inclined position in the same general direction as the surface 28 105 of the rest 24 and when engaged by the upper lip part of the mouth opening of the head cooperates with the surface 28 to the same effect as just referred to.

The term "tongue and teeth set" as herein 110 used is merely a commercial term generally used in reference to sets of the type here concerned and is here intended to comprehend any form of device arranged within the mouth or similar opening of a doll head.

As many changes could be made in this construction without departing from the scope of the invention, as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. A tool for use in attaching tongue and teeth sets in doll heads and the like, said tool comprising a standard having a portion adapted to extend into the doll head through the neck opening thereof, a set-carrier part 130

arranged at the inner end of said portion adapted to support the set thereon preparatory to attachment of the set within the head, means whereby said set-carrier part is adjustable to different positions with respect to the standard, and other means by which to apply pressure for attaching the set within the doll head.

2. A tool for use in attaching tongue and teeth sets in doll heads and the like, said tool comprising a portion adapted to extend into the head, a set-carrying part mounted upon said portion of a character to support the set and to carry the set relatively into the head, and said tool comprising also means of a character to engage and move the head for thereby effecting attachment of the set within the head.

3. A tool for use in attaching tongue and teeth sets in doll heads and the like, said tool comprising one part adapted to support the set and another part adapted to stand exteriorly of the head movable with respect to the first part to apply pressure upon the exterior 25 surface of the head in effecting attachment of the set within the head, and said second part having head-surface protecting means for directly engaging the surface of the head to protect the head during the application of 30 pressure.

4. A tool for fixing tongue and teeth sets within the mouth opening of doll heads where the sets include an attaching tang intended to be forced into the material of the head, said tool comprising one part of a character to support the set and head with the tang of the set directed toward the head, and the tool comprising a second part of a character manually operable to produce relative movement 40 between the entire set and the head for thereby driving the tang.

5. A tool for fixing tongue and teeth sets within the mouth opening of doll heads by relative movement of the set and head, said tool comprising one part of a character to support the set and to receive the doll head telescoped thereover, and the tool comprising a second part of a character operable to produce relative movement between the entire 45 set and the head for thereby effecting attachment of the set within the head.

6. A tool for fixing tongue and teeth sets within the mouth opening of doll heads, said tool having one part adapted to support the set within the head and a second part adapted to stand without the head, being cooperative with the first part to attach the set to the head said second part being of a character to apply pressure against the exterior surface 55 of the head, and a cushion member carried by the second part constituting its head-engaging portion.

7. A tool for fixing tongue and teeth sets within the mouth opening of doll heads, said tool having a part upon which the set may be mounted preparatory to application of the head thereto, by which said part is adjustable with respect to the remainder of the tool for the purpose set forth, and means to hold said part in any adjusted position to which it is 65 moved.

8. A tool for fixing tongue and teeth sets within the mouth opening of doll heads, where it is desired that the tongue portion of the set shall extend into the mouth opening of the head in contact with one wall of said opening and spaced from the opposite wall of said opening, and where the attaching operation is to be effected by relative movement between the entire set and the 75 head, said tool having a part to support the set of a character to extend loosely into the head and permit free manual movement of the head with respect to the tool, means comprised in said part to retain the set in a relatively fixed position thereon, and guide means also comprised in the tool to engage the head during relative movement of the head and tool to thereby guide the head to the mentioned desired position with respect to the 80 set.

9. A tool for fixing tongue and teeth sets within the mouth opening of doll heads, said tool having a set-carrier part shaped to cooperate with features of the set to thereby guide the set to a predetermined position upon the carrier part, and said tool comprising other means of a character operable to move the head in a direction towards said set-carried part for thereby effecting attachment of the 90 set.

10. A tool for fixing a tongue and teeth set within the mouth opening of a doll head, the set having a hollow tongue portion of non-circular cross-sectional contour, said tool having a set-carrier part provided with a non-circular protuberance to fit within the hollow 105 of said tongue portion for thereby retaining the set in a predetermined position upon the carrier part.

11. A tool for fixing a tongue and teeth set within the mouth opening of a doll head, said tool having a set-carrier part, said set-carrier part having a protuberance thereon arranged to engage within a depression of the set for thereby retaining the set in position upon the carrier part, and said carrier part also having a depression therein, spaced from the protuberance arranged to receive a protuberance of the set to thereby assist in retaining the 115 set in position.

In testimony whereof I affix my signature.

SAMUEL MARCUS.

CERTIFICATE OF CORRECTION.

Patent No. 1,706,628.

Granted March 26, 1929, to

SAMUEL MARCUS.

It is hereby certified that error appears in the printed specification of the above numbered patent requiring correction as follows: Page 3, line 67, claim 7, before the words "by which" insert the word "means"; and that the said Letters Patent should be read with this correction therein that the same may conform to the record of the case in the Patent Office.

Signed and sealed this 21st day of May, A. D. 1929.

**M. J. Moore,
Acting Commissioner of Patents.**
